SLIDING DOOR OPERATING MECHANISM

Ray E. De Camp, Glendale, and Rockwell Hereford, Pasadena, Calif., assignors, by mesne assignments, to Consolidated Western Steel Corporation, Los Angeles, Calif., a corporation of Delaware

Application November 17, 1947, Serial No. 786,464

3 Claims. (Cl. 268—72)

1

Our invention relates to an operating mechanism for sliding type doors and has particular reference to a modified mechanism for operating doors of the type disclosed in the copending application of Ray E. DeCamp, one of the present inventors, Serial No. 658,344, filed March 29, 1946, which issued as Patent No. 2,553,637 and entitled "Door and Operating Mechanism Therefor."

In this prior application there is disclosed a multi-paneled articulated type of sliding door that is suspended from swinging arms of the rolling hangers. This type of suspension not only permits the door to move in a direction parallel to its plane but also permits it to move transversely to its plane so that the door may be fitted within a door frame. This type of door is particularly suitable for refrigerated vehicles such as railway cars, highway trucks, etc., where-in a tight fit between door and frame must be obtained and at the same time the door must not swing outwardly any appreciable distance.

In view of the fact that the doors must be opened more or less fully to permit the ready loading and unloading of the vehicle, it follows that whenever the standard type of hinged door is to be opened an ample space must be provided between the wall of the vehicle and any adjacent obstruction. It frequently occurs, therefore, that the vehicle is located too closely to building walls or other obstructions to permit the standard type of hinged door to be opened. This condition is particularly true with respect to refrigerated railway cars wherein the cars may be located upon a siding adjacent a warehouse or unloading platform disposed so close to the tracks as to prevent the opening of the door even though there may be ample space provided for the removal of the contents of the car after the door has been opened.

The type of door disclosed in the above mentioned application eliminates this difficulty inherent in hinged doors by providing a sliding door that utilizes very little space. In addition, however, it obtains a tight fit within the door frame in a manner similar to hinged doors and in a manner greatly superior to the ordinary sliding door. This is obtained by the use of rolling hangers with swinging arms, together with multi-paneled doors wherein the panels are hinged or otherwise articulated.

The present invention provides a simplified operating mechanism for opening and closing doors of this type and may therefore be an im-

2

provement in the operating mechanism disclosed in that application.

It is therefore a general object of the present invention to provide a simplified operating mechanism for multi-paneled articulated doors of the sliding type.

Another object of our invention is to provide an improved operating mechanism for actuating the swinging arms on rolling hangers for doors of the type disclosed in the above mentioned application, particularly by applying a torque to the outer end of the swinging arms and thereby roll the hangers on their tracks and move the door transversely to its plane.

15 Another object of our invention is to provide an actuating mechanism for swinging arm rolling hangers that gives great leverage to an operator at the initial stage of opening and at the final stage of door closing.

20 It is a general object of our invention to also provide improvements in detail in an operating mechanism of the type described so as to make it more positive in action, simpler to use and more free from defects than those of the prior art.

25 Other objects and advantages of our invention will be apparent from a study of the following specifications, read in connection with the accompanying drawings, wherein:

30 Fig. 1 is an elevation view of the door section and door of a railway car provided with a door operating mechanism made particularly in accordance with our invention;

35 Fig. 2 is a top view of the side of the railway car of Fig. 1 but with parts broken away illustrating the position of the door panels and parts of the linkages when the door is in a closed condition;

40 Fig. 3 is a view similar to Fig. 2 but illustrating the position of the door panels of the operating mechanism during the initial stages of opening of the door;

45 Fig. 4 is a view taken similarly to Fig. 2 but illustrating the relation of the door panels when in a position to be rolled or slid along the outer side of the railway car;

Fig. 5 is an enlarged elevation view of the operating mechanism at the central part of the top of the door;

Fig. 6 is an enlarged top view of the operating mechanism of Fig. 2;

Fig. 18 is a perspective view of the hinge joint of Figs. 14 and 15;

Fig. 19 is an elevation view of a modified form of door construction utilizing only one operating mechanism;

Fig. 20 is a sectional view along the line XX—XX of Fig. 19 illustrating the door in a closed position;

Fig. 21 is a view similar to Fig. 20 but illustrating the door in a toggle position;

Fig. 22 is an enlarged elevation view of the left-hand door hanger of Fig. 19;

Fig. 23 is a sectional view along the line XXIII—XXIII of Fig. 22 illustrating the cam lock of the door hanger;

Fig. 24 is an enlarged elevation view of the central door hanger of Fig. 19;

Fig. 25 is a sectional view along the line XXV—XXV of Fig. 24 illustrating the position of the hanger when the door is closed;

Fig. 26 is a view similar to Fig. 25 but illustrating the position of the hanger arm when the door is open; and

Fig. 27 is an enlarged fragmentary view of the hinged portion of the door panels of Figs. 20 and 21 illustrating in detail the construction of the seal strips.

Although we have illustrated our invention in the drawings as applied to railway car doors, it will be readily apparent that this construction could be employed on any type of vehicle and, in fact, could quite readily be applied to stationary installations such as cold storage rooms, large refrigerators, etc. It will therefore be appreciated by those skilled in the art that the embodiment of the drawings is illustrative only and is not definitive or limiting with respect to the scope of our invention.

Referring to Fig. 1, the side of a railway car 28 may be provided with a door frame 21 in which may be disposed a multi-paneled door 22 and for purposes of illustration this door may be provided with two separate panels 21a and 22b. These panels may be hinged together and preference is expressed for the hinge structure of Figs. 14, 15 and 18 although it will be obvious from the following description that any type of

hinge structure will functionally carry out the purposes of our invention. The door 22 may be suspended from three rolling hangers including a left-hand hanger 23, a center hanger 24 and a right-hand hanger 25, all mounted on a track 26. The bottom of the door 22 may be guided by a roller guide assembly 27 making contact with a retaining strip 28.

The door 22 may be swung inwardly and outwardly of the door frame 21 by means of an operating mechanism 29 constructed particularly in accordance with our invention and disposed centrally of the door, that is, adjacent the hinge joint. The operating mechanism may include an operating handle 31 as well as a link 32 connecting the central rolling hanger 24 with the right-hand rolling hanger 25. This handle may be held in a "door close" position as illustrated in Fig. 1 by means of a lock mechanism 33 and when released from the lock it may be rotated in a horizontal plane through 180° to thereafter be retained in a second or "door open" position by lock mechanism 34. The details of the lock mechanisms 33 and 34, which are identical, are illustrated in Figs. 12 and 13.

The present operating mechanism effects opening and closing of the door 22 in the same manner as the mechanism of the prior application, that is, by applying a torque to the outer end 30 of swinging arms pivoted to the hangers supporting the door. These swinging arms are best illustrated in Fig. 1 and may be referred to generally by the reference character 35 for all of the hangers and including also the swinging arm on the lower rolling guide 27. These swinging arms 35 are so mounted on their respective rolling hangers as to have a full 120° of swing and accordingly may rotate from a position generally parallel to the car door as illustrated in Fig. 1 to a position substantially at right angles to the car door as illustrated in Fig. 4. It will be appreciated therefore that when a torque is applied to the outer ends of these arms sufficient to roll the hangers along their track, the arms will assume an increasingly larger angle with respect to the side of the railway car 28 and accordingly that portion of the door supported at the swinging arm will be moved outwardly away from the side of the car.

The swinging arms 35 of the hangers 23, 24 and 25 support the weight of the door 22 and accordingly the outer end of each swinging arm 35 may be provided with a downwardly disposed shaft 36 which may pass through bearing brackets 37 at the two sides of the door whereas the shaft 36 of the central arm 35 may pass through an actuating bracket 38. Nuts 39 may be secured to the protruding end of the shaft portions 36 so as to carry the weight of the door as the bearing brackets 37 and 38 bear against them. The arm 35 on the rolling guide 27 may be provided with an upwardly projecting shaft portion 36a passing through a lower actuating bracket 41.

The principal application of torque to the swinging arms 35 is at the central part of the door and accordingly torque is applied to the shaft 36 passing through the actuating bracket 41 at the bottom of the door. This torque is applied to these shafts by means of crank arms 42 rigidly secured to the respective shafts 36 and 36a. The crank arms 42 are connected by means of an adjustable connecting rod 43 to a crank 44 mounted for rotation in the respective brackets 38 and 41. The cranks 44 are adapted to be operated simultaneously by being secured to a common

torque rod 45. The rod 45 may be manually rotated because of a driving connection between the operating bar or handle and the rod. Therefore, rotation of the handle 31 in a horizontal plane causes the torque rod 45 to rotate and this motion is transmitted through the cranks 44, connecting rods 43 and crank arms 42 mounted on the arm shafts 36 and 36a of the associated swinging arms 35. The rotation of the arms 35 causes the center of the door to swing outwardly or inwardly according to the direction of rotation.

Referring now to the details of construction, reference may be had to Fig. 7 for an illustration of the construction of the hanger 25 which is generally similar to the other hangers 23 and 24. In that figure it will be noted that the rail 26 may have the general form of a downwardly opening channel. The hanger 25 accordingly may be provided with a weight supporting roller 46 mounted upon a body member 47 of the hanger which may have a C-shaped pivot section (Fig. 1) 48, to which the swinging arm 35 may be pivoted. The upper part of the C-shaped frame section 48 may have a guide roller 51 mounted thereon contacting the inside of the outer flange of the channel track 26. Accordingly therefore the wheels 46 and 51 cooperate, one assuming the weight and the other to guide the weight assuming wheel accurately on the track.

Referring now to the roller guide 27, reference may also be had to Fig. 7 and it will be noted that this guide may have a simplified construction. It will be noted also that the retaining strip 28 may have a downwardly depending lower edge which may be contacted by an angle iron portion 52 of the roller guide to restrain the guide from moving outwardly away from the side of the car 20. The guide may be provided with a roller 53 to contact the outer face of the retaining strip 28.

The bearing bracket 38 will next be described and this may be considered as illustrative with the substantially identical bracket 41 at the lower edge of the door. Referring particularly to Figs. 1 to 6, inclusive, it will be noted that the bracket 38 may be substantially of a single piece construction, for example, as by a forging or casting. The bearings for the swinging arm shaft 36 and for the crank 44 may be completed, however, by double recess bearing caps 54 secured at top and bottom to the bracket, for example, by screws 55 or studs and nuts. The crank arm 42 may be secured to the arm shaft 36 prior to assembly because of this split bearing construction. A crank pin 56 may be disposed in the crank arm 42 for securing the associated end of the connecting rod 43. As mentioned previously, the nuts 39 on the bottom of the arm shafts 36 support the weight of the door from the swinging arms 35. It should also be noted with respect particularly to Fig. 5 that the shaft axes of the shaft 36 and of the crank 44 (and the torque rod 45) remain fixed, the crank axis of the crank 44 being revolved and in turn driving the crank arm 42. The construction of the torque rod 45 is best illustrated in Figs. 1, 8, 9 and 10, together with the connection of the handle thereto.

Referring to Fig. 1, it will be noted that a pivot bracket 57 may be secured to one panel of the door 22, for example, the panel 22a to form a pivot upon an angled projection 58 of the torque rod 45. Further, it will be noted that

almost the entire length of the torque rod 45 is offset from its pivotal axis in the brackets 38 and 41 so that the pivot formed by the bracket 57 is at the axial pivot of the rod itself. The handle 31 may be pivotally secured to the torque rod 45 by means of a pin 59 passing through the outer end of the angle 58 and through the torque rod 45. When the handle 31 is rotated in a horizontal plane through 180°, the torque rod 45 will be disposed outwardly of the pivot bracket 57, as is clearly illustrated in Fig. 9. This outwardly disposed position provides a good manual grasp for sliding the door on its track once the door has been released from its door frame.

The lock for the operating bar or handle 31 is illustrated in detail in Figs. 12 and 13 and accordingly each lock 33 and 34 may have a base member 61 secured to the door and which may have a general L-shape to provide a socket in which the operating bar 31 may rest. Pivoted to the top of this bracket may be a dog leg member 62 adapted to close the L-shape bracket 61 so as to enclose the operating bar 31. Accordingly the bar may be locked in any position by this dog leg and the lock may be secured, for example, by passing a padlock through register apertures 63 in each element.

The operating bar 31 may be released from the lock 33-34 by rotating the dog leg 62 to the broken outline position of Fig. 12. The operating bar 31 may then be raised upwardly a slight distance to clear the outer hook of the L-shape bracket 61 and it may then be pulled outwardly away from the door. The bar 31 may be automatically locked upon closing due to a projecting portion 64 of the dog leg 62 when the dog leg is in an open position. Accordingly therefore dropping of the bar upon the open lock will cause the bar to strike this projection and rotate the dog leg to the closed position illustrated, enclosing the bar at the same time.

The presently preferred hinge structure for the door panels 22a and 22b is illustrated in Figs. 14, 15 and 18. In this connection it should be noted that a railway car or other vehicle is not a rigid unyielding structure but must be made flexible. This flexing results in frequent elastic deformation of the door frame 21 and if a solid single panel door were thrust with little clearance into the door frame the yielding and deformation of the door frame would soon crush the edges. Therefore, the hinge structure illustrated is designed to accommodate the bending and twisting of the car that results in change of shape of the door frame. This change of shape is further accommodated by the multi-panel nature of our door, permitting each panel to move independently.

Referring to these figures it will be noted that the joining edges may be recessed at the back edge thereof as at 65 to receive a pair of spring centers 66 to center a pair of springs 67. Since these springs are compression springs and are disposed toward the inner edge of the two panels, the springs will tend to push the doors apart and accordingly when resisted by a hinge structure 68 will tend to straighten the doors. The springs are prevented from straightening the door past dead center by means of a strip 60 secured to one of the panels, which strip may also be of a resilient material to act as a seal.

The hinge structure 68 may be in the form of

a simple hook 68 passing through an apertured plate 71. The clearance of the aperture in the hook is purposely made ample both vertically and horizontally to accommodate limited relative movement of the panels. Two or more such hinges may be used for each panel joint, including one at the top of the joint and one at the bottom of the point. Likewise the springs 81 may be positioned in panel joints generally opposite each hinge inasmuch as recesses must be formed for each.

A seal for the bottom edge of the door to prevent the escape of cold air may take the form of a recessed figure eight rubber seal 72 adapted to press against a ramp strip 73. A doorsill plate 74 may form the bottom part of the door frame and is preferably of heavy metal so as to receive one end of the usual loading and unloading ramp board, the inner end of which may press against the ramp strip 73. It will be noted that in the region of the door joint the figure eight seal 72 may be backed up or supported by the compression springs 81. The joint between the panels may be sealed along its length by means of a flexible fabric 76 secured to each side.

A modified form of hanger for use with our invention is illustrated in Figs. 16 and 17 and may include a frame member 78 mounted for rolling upon an angle member 76 by means of a single central roller 77. A downwardly opening channel 78 may be secured to the upper end of the angle 76 to provide a track for resisting outward pulls on the hanger and a pair of rollers 79 may fit within this channel. A swinging arm 81 may be suitably pivoted to the body member 78. The guide rollers 79 disposed on either side of the weight assuming roller 77 prevents twisting and turning of the hanger as a whole.

Referring now to the operation of our mechanism, reference may be had particularly to Figs. 1 through 6. The door 22 is illustrated in a closed condition in Figs. 1 and 2. In this connection it will be noted that the door frame 21 may include projecting tongues 21a to not only provide a seal but to also restrain the closed door from slipping outwardly. It is therefore apparent that the door cannot merely be shoved in and out but must be opened and closed with an action akin to the usual hinged door but without the geometrical limitations of a hinged door. Accordingly to open the door 22 the center joint must be first pulled outwardly as illustrated in Fig. 3 until one or both sides of the door have been pulled away from the interlocking door jamb or door frame construction. When this has been achieved, one of the edges may then be pulled outwardly, as is illustrated in Fig. 4.

This sequence of movements for opening may be effected by an operator releasing the lock 33 and rotating the operating bar 31 through a horizontal plane for 180°. He may if desired then secure the operating bar 31 in the lock 34. The initial rotation of the bar 31 is illustrated in Figs. 3 and 6a and there it will be noted that the crank 44 has been rotated through the same angle as the operating bar 31 inasmuch as they are rigidly interconnected by the torque rod 45. The crank 44 accordingly will act through its connecting rod 43 upon the crank arm 42 to rotate the shaft portion 36 of the associated swinging arm 35. The interconnection of the cranks and their angular dispositions are so related, however, that 180° of rotation of the operating bar effects only about 110° or 120° rotation of the swinging arm 35. Additionally, the arrangement of crank, connecting

rod and crank arms is so adjusted as to give greatest torque for the initial opening operation when it is most needed and for the final closing operation when it is also most needed.

This angular relation of parts is best illustrated in Figs. 2 through 6 and it will be noted that the crank arm 42 is disposed at a substantial angle to the swinging arm 35 to which it is connected. Further, it will be noted that the crank 44 is mounted on the torque rod 45 at an angle just slightly "past" the operating bar 31 so as to dispose it as closely as possible against the door panel 22b. This position of the crank 44 with respect to the crank arm 42 gives the greatest possible torque arm length or direction of thrust upon the crank arm 42 by the intermediary of the connecting rod. During the initial stages of rotation of the handle 31, therefore, the greatest available thrust will be brought to bear upon the crank 42 to thereby rotate the swinging arm 35 to which it is connected.

When the handle 31 has been rotated approximately 45°, the relation of parts is illustrated in Figs. 3 and 6a. There it will be noted that the direction of thrust upon the crank arm 42 is less favorable than initially inasmuch as it is not at right angles to the crank arm. However, the swinging arm 35 has already passed its most resistive position in that the angle of the swinging arm 35 to the roller track 28 has increased to a substantial amount.

The relation of parts at the final stage of opening is illustrated in Figs. 4 and 6b and there it will be noted that the effective leverage between the crank and the crank arm has been materially reduced due to the unfavorable direction of thrust in the connecting rod. This is not important, however, inasmuch as the swinging arm 35 is then almost at a final angle and little or no effort is required to effect the final position of the swinging arm 35.

From the foregoing description of the angular relationships at the bearing bracket 38 (and also at the bearing bracket 41) it will be realized that the maximum amount of leverage between the operating bar 31 and the swinging arms 35 is obtained at the initial opening action when this leverage is most required. With the subsequent portions of the opening action little leverage is required and accordingly a diminution in mechanical advantage is of little importance. Additionally, the drive just shown provides in effect a reduction gearing whereby 180° rotation of the operating bar 31 will result in substantially less movement of the swing arm 35.

Furthermore, it will be noted that the assembly of parts illustrated in Figs. 6, 6a and 6b is of a compact nature and there will be little projection of these parts outwardly from the face of the car door that would detract from the dimensional benefit received from utilizing this particular type of door construction and door suspension.

The opening action of the central swing hangers having now been described, it will be apparent that some means must be provided to swing at least one edge of the door outwardly from the frame after the "toggle" formed by the two door panels has been broken outwardly, as illustrated in Fig. 3. While this outward movement of one edge could be effected manually, we prefer to effect the operation mechanically and in a timed automatic sequence with relation to the opening of the center part of the door. Accordingly therefore the connecting strip 32

may be pivoted to the central swing arm 35 at a point 83 intermediate its length and may be pivoted to the swing arm 35 of the sliding bracket 25 at a point adjacent its outermost end. Preferably the connection to the arm of hanger 25 is by means of a projection 82 formed outwardly of the pivot on the outer end of the arm of the bracket 25. Therefore, when the hanger 25 is disposed inwardly of the right-hand edge of the door 22, it will be apparent that a torque must be applied to roll the hanger 25 to a position generally opposite the right-hand edge of the door so as to move that edge outwardly of the door frame 21. This action is afforded by the connecting strip or rod 32 and this action will best be observed from a comparison of Figs. 3 and 4. It should be borne in mind in this connection that the pivot axis of the supporting shaft 36 on the central swinging arm 35 is substantially fixed and that the hanger 24 moves with respect to this axis. Accordingly, therefore, the pivot point 83 of the left-hand end of the rod 32 will be translated to the left as the center part of the door 22 is moved outwardly, as illustrated in Figs. 3 and 4. This movement of the connecting rod 32 to the left will act upon the swing arm 35 of bracket 25 to roll that bracket to the right and at the same time move the right-hand edge of the door outwardly from the frame.

It will be apparent from an inspection of Fig. 1, however, that the movement of the right-hand edge of the door must take place only after the central part of the door has been moved outwardly; otherwise the projecting tongue 21a will bind the door at the frame. This sequence of operations is timed by the point of attachment 83 of the left-hand end of the rod 32 as well as the location of the pivot point on the right-hand swing arm. Thus during the initial stages of rotation of the central swing arm 35 there will be little translation of the pivot point 83 to the left and accordingly there will be no tendency for the right-hand edge of the door to be moved outwardly. However, during the final 45° of movement of the central swing arm 35 there will be a substantial translation of the pivot point 83 to the left which will act through the projection 82 to swing the right-hand bracket 25 and move the right-hand edge of the door outwardly after the toggle has been broken.

Once the door has reached the position illustrated in Fig. 4, the left-hand edge of the door may be released by operating a handle 84 (Fig. 1) on an eccentric type of catch 85 that contracts a projecting pin 86 on the railway car. This will release the left-hand edge of the door and thereafter the door may be manually pushed toward the right and at the same time an outward pull may be placed on the left-hand edge of the door, causing it to swing outwardly on the swing arm 35 of the rolling hanger 23. This action is aided by the compression springs 67 (Figs. 14 and 15) at the panel joint. The door will then be perfectly parallel to the side of the railway car 20 and may be rolled sufficiently far to the right on the track 26 with the assistance of the lower retaining strip 28 until the doorway 21 is completely cleared. This rolling may be performed by pushing against the torque rod 45 which will project outwardly from the door when the door is open, as illustrated clearly in Fig. 9.

When it is desired to close the door, the door

is manually pushed toward the left until the left-hand swing arm 35 that is attached to the hanger 23 strikes a projecting cam 81 (Fig. 11), causing that swing arm to be rotated from a perpendicular position to a position parallel with the side of the car. The door will then be in the position illustrated in Fig. 4 and the manual latch handle 84 (Fig. 1) may then be operated to lock the left-hand edge of the door to the door frame 21. The operating bar 31 will at this time be held in the latch 34 which may be opened by rotating the dog leg 62 (Fig. 12) upwardly so as to release the bar. The bar 31 may then be rotated through a horizontal plane 180° to effect the closing.

The initial closing motion of the bar 31 will act through the torque tube 45 and consequently the crank 44 and connecting rod 43 and crank 42 to rotate the central swing arm 35 in a clockwise direction, as viewed in Fig. 4, about the axis of the downwardly depending swing arm shaft 36. While there will be very little movement of the central part of the door into its door frame during this initial angular movement, this movement will be conveyed through the rod 32 to act on the short projection 82 to roll the right-hand swing arm 35 in a counterclockwise direction at a relatively rapid rate. For this reason the right-hand edge of the door will be positioned within the door frame 21 when the central swing arm is rotated about 45°. Thereafter further actuation of the handle 31 will cause the central swing arm 35 to be rotated to the position illustrated in Fig. 2 wherein the door will be completely closed. The closed door will be prevented from sliding outwardly from its door frame because of the projecting tongues 21a in addition to the bearing of the hanger swing arms inwardly to hold the door in position.

It should be noted that during the final stages of closing the greatest amount of torque must be applied to the central swing arm 35 and that the construction of the crank 44, connecting rod 43 and crank arm 42 is particularly adapted to give the maximum amount of mechanical advantage to the operator using the handle 31 at this time. Thus it will be noted that in Figs. 2 and 6 the connecting rod 43 is substantially at right angles to the crank arm 42, this giving the maximum amount of power transfer between the torque rod 45 and the crank arm 42. The mechanical advantage of the linkages will be less during the initial closing stages, as is clearly illustrated in Figs. 4 and 6b but this is of little consequence inasmuch as relatively little power is required at this stage of the closing to move the door into position.

Once the door is fully closed, as illustrated in Figs. 1 and 2, the side walls thereof will be sealed against the leakage of air by means of the projecting tongues 21a which may, if desired, be of resilient material such as rubber. The bottom of the door will be sealed as illustrated most clearly in Fig. 14 because of the bearing of the figure eight seal 72 against the ramp strip 73. During movement of the railway car the door frame will change its shape as the car elastically deforms and weaves while traveling but this change in shape will be accommodated by the two-panel construction of the door 22, namely, the panels 22a and 22b. The relative sliding of the door panels will be accommodated by the hinge construction at the central part of the door, as most clearly illustrated in Fig. 18.

It will be noted from an inspection of Fig. 1 that the operating mechanism may incorporate standard units that can be employed on any size of door, the only changes being required for different sizes of doors residing in the length of the torque rod 45 and the length of the interconnecting strip 32. Also for doors of different thickness, hanger arms of different lengths may be employed. The invention therefore makes feasible the mass production of these door elements, permitting field installation to accommodate different sizes by merely varying these two elements only.

Additionally, it will be noted from Figs. 8 and 9 that the offset character of the pipe not only makes possible a stronger connection of the operating handle 31 to the torque rod 45, but also is combined with a pivot structure 57 at the point where the torque is applied to the torque rod 45. Therefore the torque rod 45 not only projects outwardly for a maximum manual grasp when the door is open but also is ideally constructed for hard service and long life. The latch mechanisms 33 and 34 (Figs. 12 and 13) are rugged and simple to provide for effective locking of the operating bar 31 in either a door open or door closed position.

Referring to Fig. 19, there is illustrated a modified form of door construction disposed upon an illustrative freight car 98 wherein the door may include two panels 91a and 91b. The door may be of the same general type as that of Fig. 1 in that it is articulated at the middle and closes with a toggle action and is supported by a plurality of rolling hangers, a left-hand hanger 92, a central hanger 93, and a right-hand hanger 94, all of which may be of the same general construction. The principal difference between the door of Fig. 19 and that of Fig. 1 is in the use of a single operating mechanism 95 to which may be attached an actuating handle 96, and the resulting motion from which may be transmitted by a torque tube 97 to actuate swing arms 98 forming a part of the central hanger 93 and also forming a part of a lower guide 99.

The door construction of Fig. 19 does not rely merely upon the rotation of the swing arms of the hangers to maintain the door closed, but instead incorporates a six-point locking action including a locking of the right edge of the door by two bar locks 101, a cam closure action on the left-hand hanger 92, and a cam closure action on a manual latch 102 disposed at the lower portion of the left-hand edge of the door. The other two points of retention include the central hanger 93 and the lower guide 99.

The operation of the bar locks is illustrated with reference to Figs. 20 and 21. There it will be noted that the bars 101 may slide in grooves 102 that have a considerable dimensional tolerance. The bars 101 may be secured to the opposite panel 91b by means of a projecting rod 103 disposed at the joint between the panels and including a pin connection 104 to the respective bar locks 101. When the door is closed, as illustrated in Fig. 20, the bar locks 101 may project into recesses 105 formed in the edge of a door frame 106 into which the door panels 91 fit.

The action of the bar locks 101 is effected by opening the doors in toggle position as illustrated in Fig. 21, and the central disposition of a hinge structure 107 between the panels gives a spreading of the panels at their outer edge which causes the projecting rod 103 to pull on the bar locks 101 to withdraw them out of their locking recesses 105. As the doors are closed with the

action described relative to Figs. 2, 3, and 4, the bar locks will be withdrawn upon closing in toggle position, and will project upon full closure, as illustrated in Fig. 20. The use of the bar locks 101 makes unnecessary a dependence upon the closing action of the right-hand hanger 94, and accordingly the door frame 106 may be perfectly square or flat inasmuch as no reliance is needed for projecting tongue and grooves to hold the door in locked position. This greatly facilitates the construction of the door frame and the edges of the door panels.

The operating mechanism 95 of Fig. 19 may be essentially that described with reference to Figs. 5 and 6, except that the handle 96 may be pivoted to the outer crank portion 95a, thus applying power directly to this member instead of applying it indirectly through a torque rod as illustrated in Figs. 5 and 6. The resultant motion of the torque rod 97 acts upon the outer ends of the swing arms 98 to move the door inwardly or outwardly according to the direction of rotation.

The upper rolling hanger 93 is illustrated in detail in Figs. 24, 25 and 26, and may be essentially similar to the rolling hanger illustrated in Figs. 16 and 17. Accordingly the hanger 93 may include a weight assuming wheel 108 which is maintained on its angular track 109 by means of two guide rollers 111. A pressure relieving shoe 112 may be employed that is mounted on an eccentric post 113 projecting upwardly from a swing arm shaft 114 secured by a pin 115 to the swing arm 98. The weight supporting element 30 of the rolling hanger 93 may be a C-shaped frame 116 having a stub shaft 117 threaded therethrough and which may be recessed to receive a ball 118 that assumes the thrust due to the weight of the door.

The central hanger 93 may be interconnected to the right-hand hanger 94 by a rod 119 interconnecting the swing arms of these two hangers. This rod may operate in a fashion similar to the rod 32 of Fig. 1, and its attachment to the central rolling hanger 93 is illustrated in Figs. 24 and 26 as including a pair of projecting ears 121 between which may be pivoted a screw eye 122 adapted to be threaded into the rod 119 for length adjustment.

50 The camming action of the left-hand hanger 92 that was previously mentioned is illustrated in detail in Figs. 22 and 23. There it will be noted that a bracket 123 attached to the door panel 91b for receiving the swing arm 92a of the rolling hanger may be provided with a projecting tongue 124. This tongue is adapted to project in a hook 125 when the door is closed as is illustrated in Fig. 23. The swing arm 92a may also contact cams (not shown) similar to the construction illustrated in Fig. 11 for effecting an initial closure of the left-hand edge of the door. When the door edge is disposed substantially within the door frame, the projecting tongue 124 will fit within the hook 125, and as the door is moved from a toggle position to a flat closed position, the tongue and hook will solidly engage to maintain the door in a locked position.

A similar camming action may be incorporated in the manual latch 102 of Fig. 19, and this camming action is illustrated in Figs. 20 and 21. Accordingly the manual latch may include a catch member 126 adapted to engage a projecting pin 127. Mounted on the same bracket with the pin 127 may be a hook member 128 that will engage an angled end 126a of the catch. Accordingly

when the left-hand door edge is disposed within the frame, the catch 126 may be locked over the pin 127 and as the door rotates to a flat closed position, the angled end 126 will make a positive engagement with the hook 128 to secure the left edge of the door as illustrated in Fig. 20.

The structure of the door panels 91a and 91b at the region of the joint or hinge is illustrated in detail in Fig. 27. There it will be noted that the hinge 107 may be formed of oppositely disposed plates having hooks formed on the end thereof and having a pin 107a passing between them. As is also the case with the hinge structure of Fig. 18, there is preferably a fair amount of play between the opposite hook members along the axis of the pin 107a. This allows the door panels to move relative to each other in response to twistings of the railroad car 90 during transit or other maneuver. The inner edge of each panel 91 may be provided with a recess 129, each including a raised rib 131 extending substantially the entire height of the door. Each panel may also be provided with an overlapping plate 132 having edges spaced from each other a distance sufficient to allow the panels to assume a large angle with respect to each other. A fabricated strip board 133 may be disposed between the plates 132 and the projecting ribs 131 to act as a seal and thermal insulation for the joint between the panels. This strip board may include a channel-shaped member 134 in which may be disposed a sheet of fabric, rubber, or other flexible material 135, and a wear strip 136 may be fitted within the channel on top of the sheet material 135. The sheet material 135 may extend between the inner plates 132 on the body of the panels.

The action of the sealing strip 133 upon flexing of the door is illustrated in Fig. 21, and there it will be noted that the strip 133 in effect divides the angle between the panels and maintains a tight seal that will accommodate this flexing of the panels. The sheet material 135 at all times maintains an absolute seal against the passage of air, whereas the body of the strip 133 acts as very ample thermal insulation. If desired, springs may be supplied for the door such as those illustrated in Figs. 14 and 15 to assist in the straightening of the panel either upon opening or closing.

The operation of the door of Fig. 19 is generally similar to that of Fig. 1. Assuming that the door is closed as illustrated in Fig. 19, an operator may unlatch the handle 96, may then rotate the handle which causes the outer crank 95a to rotate, and this motion in turn is imparted to the torque rod 97 to act on the outer end of the swing arms 98 to move the center part of the door outwardly as illustrated in Fig. 21. Movement of the door to the position illustrated in Fig. 21 removes the lock bars 101 from their recesses 105, unlatching the right side of the door, and thereafter the motion of the upper swing arm 98 acts through the connecting rod 119 to swing the arm of the right-hand hanger 94 to move the right-hand edge of the door outwardly to the position generally illustrated in Fig. 4. This position, and in fact the position illustrated in Fig. 21, releases the retaining cams 124 and 126 (Figs. 23 and 21, respectively) so that the left edge of the door is free to move. Manual action or the action of any springs incorporated in the hinge between the panels will then move the left edge outwardly so that the

entire door is parallel to the railway car 90. An operator may then push against the torque rod 97 or any other part of the door so that the door rolls freely on its hangers 92, 93, and 94 to provide free access to the doorway or door frame 106.

On closing, the entire door may be rolled along the track 108 until the swing arm of the left-hand hanger 92 contacts a cam, for example a cam similar to that of Fig. 11, and the swing arm is then progressively rotated until the left edge of the door is disposed within the door frame in the general position illustrated in Fig. 4. Thereafter the operator may rotate the handle 96 from right to left, causing a rotation of the torque rod 97 which rotates the upper and lower hangers 98. The closing action of the upper hanger 98 is imparted through the rod 119 to the swing arm of the right-hand hanger 94, causing that hanger to dispose the right edge of the door inwardly as illustrated in Fig. 21. Further rotation of the handle 96 to the position illustrated in Fig. 19 causes the entire door to become flat within the door frame 106, as illustrated in Fig. 20. The last part of the closing action causes the lock bars 101 to project within their locking recesses 105, and this closing action also causes the cam members 124 and 126 to act against their respective hooks 125 and 128 to lock the left edge of the door also. The center of the door is locked by the action of the torque rods 97 on the outer ends of the swing arms 98.

While we have described our invention with respect to specific embodiments thereof, we do not limit ourselves to these embodiments since it is obvious that various modifications could be made therein without departing from the true spirit and scope of our invention. For example, it will be apparent that a gearing could be used at the brackets 38 and 41 instead of a crank and rod, but we prefer the crank and connecting rod inasmuch as these are more rigid and in addition can be suitably adjusted. Additionally, it may be desirable to support the center weight of the door for the initial opening and final closing stages by having an outwardly projecting cam or support bracket engaged either by the door or by a projecting end of the torque rod 45 or its extension.

Further, it will be obvious that no particular type of door panel construction is contemplated and that our invention may be employed with any type of multi-paneled door. While two panels are illustrated, it is obvious that any number of panels could be effectively operated. Further, the hangers could be rolled in either direction of the swing arm shafts to effect opening and closing. Also, a connecting link between the left-hand hanger and the central hanger could be employed for moving the left edge at the proper time.

For these and various other reasons the disclosure made in this application is merely illustrative and not definitive of our invention.

We claim:

1. In a mechanism for operating a refrigerator car door of the type including a panel adapted to be bodily set into and pulled out of an opening in the car wall defined by spaced jambs, a lintel and a sill, a pair of arms pivoted on hangers adapted to travel horizontally above said lintel, said arms extending above the upper edges of the door and having pivot pins depending therefrom and journaled on the outer face of the door, a manually operable torque rod extending

vertically of the door, and connecting means whereby rotation of said rod turns one of said arms, the combination therewith of a crank on the other of said arms, and a link pivotally connected to said crank and to a point on said one of said arms intermediate the ends thereof effective to transmit angular motion from said one of said arms to the other.

2. In a mechanism for operating a refrigerator car door the combination therewith as defined in claim 1 characterized by said crank arm and said point being disposed and located to actuate the second arm only after initial angular motion of said one of said arms, whereby one edge of the door is moved only after initial movement of the other.

3. In a mechanism for operating a refrigerator car door the combination therewith as defined in claim 1 characterized by the distance from the pin of said one of said arms to said point being greater than the length of said crank.

RAY E. DE CAMP.
ROCKWELL HEREFORD.
